(57) **CLAIM**

The ornamental design for a baby crib, as shown and described.

DESCRIPTION

FIG. 1 a perspective view illustrating my new design;

FIG. 2 is an elevational view from the headboard end thereof, it being understood that the elevational view from the footboard end is a mirror image thereof;

FIG. 3 is a left-side elevational view thereof, it being understood that the right-side elevational view is a mirror image thereof;

FIG. 4 is top plan view thereof; and,

FIG. 5 is a bottom plan view thereof.

The broken lines are for environmental purposes only and form no part of the claimed design.
